GEOGRAPHICAL CLOCK

Crispin B. Segovia, New York, N. Y.

Application April 16, 1935, Serial No. 16,700

4 Claims. (Cl. 58—44)

This invention relates to geographical instruments and particularly to an improved clock for indicating the time of day at various points over the entire earth, the structure being such that not only the particular hour is indicated but also whether it is morning or evening, or day or night.

An object of the invention is to provide a clock which has the usual clock mechanism now well known and, in addition, means for indicating on a traveling tape the hour and also information as to whether it is day or night.

Another object of the invention is to provide a geographical clock presenting the names of different points or places and indicating the time of day at the respective places.

An additional and more specific object is to provide a geographical clock in which one or more traveling tapes may be used for indicating more or less the time of day at a large number of points on the earth.

In the accompanying drawings—

Figure 1 is a front view of the complete clock as it appears when in use;

Fig. 2 is a vertical sectional view through the structure shown in Fig. 1, the section being taken on the line 2—2 of Fig. 3;

Fig. 3 is a sectional view through Fig. 2 approximately on the line 3—3;

Fig. 4 is a front view of a modified form of clock to that shown in Fig. 1 wherein only a single traveling tape is used;

Fig. 5 is a view similar to Fig. 2 but showing a single tape instead of a double tape.

Referring to the accompanying drawings by numerals, 1 indicates a casing which may be wood, metal, or other material, said casing having a brace 2 secured therein by any desired means, as, for instance, screws. This brace is near the edge of the casing, while the front 3 is provided with openings 4 and 5, each opening having a suitable glass or plate 6 arranged therein so as to close the casing and prevent dust from entering. As shown in Fig. 2, there are provided tapes 7 and 8. As these tapes are identical a description of one will apply to both.

As Fig. 3 is taken through Fig. 2 on the section line 3—3, the tape 7 will be readily seen back of the plate 6 in the opening 5. This tape and tape 8 are each provided with equally spaced numbers or legends 9 indicating hours and adjacent these numbers are suitable graduation marks 10. If desired, a number of graduation marks may be positioned between the numbers or legends 9. The numbers 9 are spaced one hour apart and 55 are arranged to indicate the hours of the day,

there being a sufficient number to indicate two days on each tape. In addition to the numbers 9 and graduations 10, there are provided two shaded areas 11 for indicating night-time, namely, from six o'clock in the evening to six o'clock 5 the next morning, or a twelve-hour period. The tape 8 is positioned to move as indicated by the arrow 12 in Fig. 1, and when the tape is positioned as shown in Fig. 1, it indicates that the time is six thirty a. m. at London, Madrid and Paris. 10 The same arrangement is made in regard to the tape 7 which is seen through the opening 5. At the same time that it is six thirty a. m. in London, it is six thirty p. m. at Pago-Pago. It will be understood that the tapes 7 and 8 move simultaneously and in the same direction, namely, as indicated by the arrows 12 and 13, a movement of the respective tapes causing actuations of certain mechanisms which will now be described.

As indicated in Fig. 3, the housing 14 indicates 20 a clock of any desired kind having the usual hour-hand 15 (Fig. 1) and minute-hand 16. The minute-hand 16 is secured to a suitable minute shaft 17, which makes one complete rotation in an hour. To the minute shaft 17 is connected a 25 driving shaft 18 which carries a gear 19 meshing with a gear 20. The gears 19 and 20 may be of any suitable kind, as, for instance, spiral gears, and their gear ratio is two to one as far as function is concerned, whereby one revolution of the 30 shaft 18 will produce one-half a revolution of the gear wheel 20. The gear wheel 20 has a driving shaft 21 rigidly secured thereto, said driving shaft being supported by suitable brackets 22 carried by the brace 2 and also by brackets 23 and 24 35 carried by the casing 1. Sprocket wheels 25 and 26 are secured to the shaft 21 and have their teeth continually meshing or fitting into the perforations in the respective tapes 7 and 8, whereby whenever shaft 21 is moved the tapes will also 40 be moved. The parts are so proportioned that upon one-half a revolution of the gear wheel 20 the tapes will move forwardly a distance of one hour, which is the space between any two legends 45 or numbers 9.

When the construction is used as shown in Figs. 1, 2 and 3, there will be the usual clock face, as illustrated in Fig. 1, over which the usual hands 15 and 16 move as well as the usual second hand 16'. In addition to this clock face the respective 50 tapes 7 and 8 will be so placed that a person at any of the places indicated on the clock may observe the time of day it is, and also the time of day at many other places. From Figure 1 it will be observed there is a column 27 contain- 55

- ing names and also a column 28 containing names, and opposite each name or group of names there is a graduation mark, said graduation marks being spaced one hour apart to agree with the hour graduations on the tapes 7 and 8. It will be understood that other names may be used in the columns 27 and 28 than those shown, these names being shown merely to illustrate the idea.
- 10 As the tapes 7 and 8 are both four times as long as the amount shown in Fig. 1, they are preferably supported as shown in Fig. 3, namely, by the respective sprockets and idlers 29 and 30. In addition, for each tape there is a tension roller 31 carried by a shaft 32, which, in turn, is supported by a swinging arm 33 pivotally mounted at 34 on the casing 4. The roller 31 may produce the desired tension by gravity, but preferably it is made comparatively light and a retractile spring 35 is used to maintain the desired tension so that the parts will function accurately regardless of the position in which the clock may be placed.
- Instead of having two tapes in the particular mechanism shown in Fig. 2, the invention contemplates the use of a single tape in combination with the same clockwork 14 as indicated in Fig. 3, which is preferably an ordinary standard clock. As shown in Figs. 4 and 5, there is a single tape 37 which is preferably of the same length as the tape 7 and provided with perforations so as to be driven by a sprocket wheel 38 in a similar manner to that in which the tape 7 is driven. The tape 37 is supported by the same kind of idlers, namely, 29 and 30, and also by the sprocket wheel 38 with the tension roller 31 being used in the same manner as shown in Fig. 3. However, instead of having the driving shaft 21 and detail structure associated therewith, the sprocket wheel 38 is provided with a shaft 39 to which a gear wheel 40 is secured, which gear wheel meshes with a pinion 41. The pinion 41 is secured to the minute shaft of the clock in any desired manner so that the ratio between the pinion 41 and gear 40 is two to one, whereby the sprocket wheel 38 will move the tape 37 a distance of one hour when pinion 41 rotates once. As shown in Fig. 4, there are columns 27' and 28' having the names of places or points on the earth with indicating marks arranged adjacent thereto and adjacent the opening 4' whereby the relative position of the tape 37 and the names of the different points or cities may be readily seen, but in this form of the invention the tape is moved downwardly, as indicated by the arrow 42, and the tape is provided with shaded portions 43 and 44 on opposite sides to indicate the night-time of the respective days provided on the tape. For instance, as shown in Fig. 4, it is six o'clock A. M. in London and Paris and six o'clock P. M. at Pago-Pago. As the tape is moving downwardly it indicates that the day is just starting in London and is just ending in Pago-Pago. Aside from the details just set forth the structure shown in Figs. 4 and 5 is identical with that shown in Figs. 1 and 2.
- I claim:
1. A geographical clock, including a casing, a standard clock mechanism having a minute shaft, a driving shaft connected with the minute shaft so as to rotate at the same speed as the minute shaft, a pair of tapes, each tape having graduations thereon indicating hours and shaded zones indicating night-time, said shaded zones being spaced apart so that when the tapes are

5 moved past a given point the proper indication will be made as to the time of day at that given point and also whether it is day or night, said casing having an opening in the face thereof for each of said tapes, said openings being sufficiently long to expose enough of each tape to present to view twelve hours, means for indicating names of places, on the earth, arranged alongside of each of said openings, the places indicated by the names adjacent one opening being located in one hemisphere and the places indicated by the names adjacent the other opening being located in the opposite hemisphere, means for supporting said tapes while permitting the same to move past said openings longitudinally thereof so that the graduations thereon may be moved past said place-indicating means, said means including a sprocket wheel for each tape, a single shaft rigidly connected to both of said sprocket wheels, a gear wheel 20 rigidly secured to said shaft, and a second gear wheel rigidly secured to said driving shaft, said second-mentioned gear wheel meshing with the first-mentioned gear wheel, and said gear wheels being of a ratio of two to one so that the rotation 25 of said driving shaft one revolution will move both of said tapes a distance equal to one hour.

2. A geographical clock, including a casing having a pair of parallel openings, tapes having graduations thereon indicating not less than 30 forty-eight hours and shaded zones indicating twelve hours, said shaded zones being spaced along the tapes at distances of twelve hours apart so that the shaded zones may indicate night and the unshaded zones day, a pair of supporting 35 guide rollers for said tapes, a pair of driving sprocket wheels for said tapes, a standard clockwork connected to said sprocket wheels for rotating the same at a speed whereby said tapes will move past a given point at the rate of one 40 graduation per hour, and means on the casing arranged alongside said tapes presenting the names of specified points on the earth, the places indicated by the names adjacent one opening being located in one hemisphere and the places 45 indicated by the names adjacent the other opening being located in the opposite hemisphere.

3. A geographical clock adapted to indicate the time of day at certain points over the entire surface of the earth, comprising a casing having a 50 face, means on the face for indicating in two columns the names of places, one column indicating the names of places on one-half the earth and the other column indicating places on the other half of the earth, an opening in said casing 55 opposite each row of names, a traveling tape for each opening, said tapes moving longitudinally of the openings, continually exposed graduations on the tapes indicating twelve hours, a standard clock mechanism arranged in the casing, and 60 means driven by said clock mechanism acting to move said tapes simultaneously at a rate whereby a given point on the respective tapes will move the full distance of the respective openings in twelve hours.

4. A geographical clock having a casing with a front face, said front face having a pair of parallel openings therein, a row of names on one side of each of said openings, the names adjacent one opening being located in one hemisphere and the 70 names adjacent the other opening being located in the opposite hemisphere, an indicating line extending from each of said names to the opening, an endless tape for each opening, a pair of rollers for each tape arranged within the casing, said 75

rollers being arranged above and below the respective openings, said tapes being mounted to move over said openings, said tapes having graduations thereon indicating hours, said openings being of a length to expose twelve hours on the respective tapes, a driving structure for driving said tapes, a standard clock construction ar-

ranged in said casing, and means for connecting the clock mechanism to said driving structure for driving said driving structure and said tapes at a rate which will move said tapes so that any one of the graduations exposed will move from one given point to another in one hour. 5
